UNITED STATES PATENT OFFICE.

HOVEY J. SPARKS, OF ST. LOUIS, MISSOURI.

DESIGN FOR A SANITARY BACON-HANGER.

45,730.

Specification for Design.

Patented May 5, 1914.

Application filed February 18, 1914. Serial No. 819,583. Term of patent 7 years.

To all whom it may concern:

Be it known that I, HOVEY J. SPARKS, a citizen of the United States, and resident of St. Louis, State of Missouri, have invented a new, original, and ornamental Design for Sanitary Bacon-Hangers, of which the following is a specification, reference being had to the accompanying drawing, forming part thereof.

Figure 1, is a perspective view of a sani-

tary bacon hanger, showing my new design. Fig. 2, is an edge view of the same.

I claim:

The ornamental design for a sanitary bacon hanger, as shown.

HOVEY J. SPARKS.
